DESIGN FOR A UTENSIL HANDLE

Edna M. Oster, Kewaskum, Wis., assignor to Kewaskum Utensil Company, Kewaskum, Wis.,
a corporation of Wisconsin

Application December 7, 1946, Serial No. 135,327

Term of patent 14 years

(Cl. D44—29)

To all whom it may concern:

Be it known that I, Edna M. Oster, a citizen of the United States, residing at Kewaskum, county of Washington, State of Wisconsin, have invented a new, original, and ornamental Design for Utensil Handle, of which the following is a specification, reference being had to the accompanying drawing, forming a part thereof.

Fig. 1 is a perspective view of a utensil handle, showing my new design;

Fig. 2 is an enlarged side elevation of the handle; and

Fig. 3 is a front elevation of the handle.

I claim:

The ornamental design for a utensil handle, as shown.

EDNA M. OSTER.
